UNITED STATES PATENT OFFICE.

FERNANDO CASABLANCAS, OF SABADELL, SPAIN.

SPINNING-FRAME.

1,254,390.

Specification of Letters Patent. Patented Jan. 22, 1918.

Application filed July 17, 1917. Serial No. 181,149.

To all whom it may concern:

Be it known that I, FERNANDO CASABLANCAS, subject of the King of Spain, residing at Sabadell, Barcelona, Spain, have invented 5 certain new and useful Improvements in Spinning-Frames, of which the following is a specification.

This invention refers to the spinning frames and similar machines in which, in 10 order to convey the roving to the drawing cylinders two endless belts guided by suitable guiding rollers are employed, which belts grip the roving exerting pressure upon it and convey it to a point near to the drawing cylinders. My invention specially refers to the spinning frames of this kind 15 that are described in my former Patent No. 1,147,676 and in my patent application Serial No. 11,303 filed the 1st of March 1915.

20 The machines of my former patents and in general all the spinning frames in which two endless belts are employed to grip the roving and convey it to the drawing cylinders, although they produce a work of excellent quality, they present the disadvantage 25 that the lower belt is inaccessible and in the event that it becomes broken or spoilt it is very difficult to repair it, as it is necessary to stop the machine and to withdraw 30 the upper belt and the guiding rollers of same, in order to attain the lower belt, and if this belt has to be withdrawn it is necessary to disassemble the driving cylinders taking a great amount of time and work.

35 My invention has for object to obtain a spinning frame similar to the machines described in my cited former patents in which all these troubles due to the use of the lower belt are prevented thus obtaining a machine 40 of simple construction and steady working and giving good results in the most cases.

My invention consists in the use of a single endless belt that slides over a fixed plate to convey the roving to the drawing 45 cylinders. This belt is guided by rollers and is suitably tight so that it fits against the plate and exerts over it a certain pressure in order to grip the roving. The roving passes between the plate and the belt 50 and is dragged along by the motion of the belt, being compelled to advance slowly toward the drawing cylinders following the movement of the belt. At the same time owing to the pressure that the belt exerts on 55 the plate, the required retention of the roving is obtained to prevent that the fibers that

are seized by the drawing cylinders drag along the other fibers of the roving that have not yet been seized by the drawing cylinders.

With my invention I prevent completely 60 the inconveniences of the machine already known, as the plate is fixed on the machine and therefore cannot be deranged and if the belt is deranged, as it is placed over the plate, it is very accessible and therefore easy 65 to repair or substitute without interrupting the working of the spinning frame.

In describing my invention in detail reference will be had to the accompanying drawings wherein like symbols refer to like 70 or corresponding parts throughout the several views and in which:

Figure 1 is a cross section of the drawing mechanism of a spinning frame according with my invention, Fig. 2 is a plan view 75 of this mechanism and Fig. 3 is a detail. In Fig. 2 the standards and the supports of the lower cylinders have been omitted for greater clearness, leaving merely the arms that support the upper cylinders. Moreover 80 in the right hand part of the Fig. 2 only the upper cylinders with the belt have been shown, the lower cylinders being supposed to be cut away while in the left hand part, the lower cylinders are shown with the plate, 85 the upper cylinders being supposed to be cut away.

The mechanism represented in the drawings comprises a pair of drawing cylinders 3, a pair of intermediate cylinders 86, 87 90 and a pair of feeding cylinders 88, 89, as in the drawing mechanisms of the usual spinning frames. The standards 72 that carry the whole mechanism, as well as the support 82 that carries the lower cylinders 95 and the arms 80 that carry the journal bearings of the upper cylinders are of a similar construction as the ones used commonly in the drawing mechanisms of the spinning frames or other textile machines.

This invention consists of disposing between the cylinder 87 and the lower drawing cylinder 3, a plate 9 fixed on the supports 82 with screws 10, which plate has its upper face corresponding approximately to the tangent plane of the cylinders 3, 86, 87; said upper face of this plate 9 may be flat or slightly convex. Over this plate 9 rests an endless belt 1 disposed embracing the cylinder 86 and a roller or rod 5 of small 110 diameter located very near to the drawing cylinders 3. This rod 5 is supported by

means of resilient supports 29 which tend to press the rod 5 and therefore the belt 1 against the plate 9. The strength of these supports 29 may be adjusted by means of respective screws 30 screwed to the plate 9 and which serve at the same time to fix said supports 29 to the suitable position. The belt 1 is mounted tight on the cylinders 5 and 86 in order that through the tension of the belt 10 and the pressure that the cylinders exert the belt bears on the plate 9 with sufficient force to retain the roving.

The upper cylinders 3, 86, 88 lean upon the lower corresponding cylinders, either by 15 their own weight or by additional weights and therefore they are dragged along in their movement by the lower cylinders in the usual manner. The roving 11 passes between the belt 1 and the cylinder 87 and then 20 between this same belt 1 and the plate 9 to be delivered to the drawing cylinders 3. The cylinder 86 exerts a strong pressure over the belt 1 and the roving 11 forcing therefore the belt 1 to follow its movement, and this 25 belt in the part that bears against the plate exerts a softer pressure on the roving, sufficient to retain the roving and oblige it to advance following the movement of the belt, but at the same time allowing the fibers of 30 the roving that are caught by the drawing cylinders to slide between the other fibers of the roving and between the belt and the plate following the speed of the drawing cylinders and without dragging along with 35 them the other fibers that have not yet been caught by said drawing cylinders.

If for any reason during the working of the machine one of the belts is broken or split the corresponding cylinder 86 can be 40 readily lifted, and roller 5 and belt 1 be withdrawn without interrupting the working of the machine. Then the belt may be repaired or substituted by a new one, the rollers replaced in the machine and the 45 spindle corresponding to the damaged belt may be started again.

I have shown and described a preferred and satisfactory construction but desire it to be understood that slight changes may be 50 resorted to without departing from the spirit and scope of my invention, provided such

changes fall within the scope of the appended claims.

I claim:

1. In a spinning frame, an endless belt to 55 convey the roving to the drawing cylinders, a fixed plate over which said belt slides, said belt being tight and pressed against the plate, the roving passing between said belt and plate so that it is dragged along by the 60 movement of the belt and conveyed to the drawing cylinders.

2. In a spinning frame, a fixed plate over which slides the roving, an endless belt that slides over said plate and drags along in its 65 motion the roving, a pair of driving cylinders that grip said belt and roving and drive them, and a guiding rod for the front curve or loop of the belt; being said belt tight between said guiding rod and the upper driving cylinder; said guiding rod being mounted so as to press the belt against the fixed plate, in order that the motion of the belt drags along the roving conveying it to the drawing cylinders and the pressure of the 75 belt on the roving retains it sufficiently to prevent that the fibers caught by the drawing cylinders may drag along with them the other fibers that have not yet been caught by said drawing cylinders. 80

3. In a spinning frame, the combination of a fixed plate over which slides the roving, an endless belt that slides over said plate and drags along the roving in its motion, a rotary driving cylinder that drives said belt 85 to convey the roving to the drawing cylinders, a guiding rod located very near to the drawing cylinders that guides the front curve or loop of the belt, said belt being suitably tight between said driving cylinder 90 and said guiding rod; a spring acting on said guiding rod to press the belt against the plate in order that the belt drags along the roving in its motion conveying it to the drawing cylinders, and the pressure of the 95 belt over the roving produces over it a sufficient retention to prevent that the fibers caught by the drawing cylinders can drag along with them the other fibers that have not yet been caught by the drawing cylinders. 100

In testimony whereof I affix my signature.

FERNANDO CASABLANCAS.
